[57] ABSTRACT

The concentration with location at which a mobile reservoir fluid is contained within subsurface earth formations is measured by gas drilling a borehole into the earth formations while circulating a gaseous drilling fluid that is initially substantially free of the mobile reservoir fluid and measuring the concentration of the reservoir fluid in the earth formations by measuring the difference in its concentration in equivalent portions of the drilling fluid that enters and leaves the borehole.

GAS DRILLING SOIL SAMPLING

BACKGROUND OF THE INVENTION

The invention relates to an exploration process for locating a subterranean reservoir. It is particularly useful for locating a petroleum reservoir under dry land.

A mobile reservoir fluid, such as a light hydrocarbon or an inorganic gas, tends to escape from a reservoir and migrate up toward the surface of the earth. The migrating fluid flows through permeable earth formations containing interconnected pores or fractures that are normally filled with at least one natural fluid, such as water or air. The migrating mobile fluid tends to rise above and/or be dispersed in the fluid in the rock, due to effects such as gravity segregation and/or diffusion. Some of the migrating fluid is adsorbed on the surfaces of the rocks.

Previously proposed procedures for locating petroleum reservoirs measure the concentrations with location of the hydrocarbons that are contained in core samples, those contained in bit cuttings, those that become entrained in circulating liquid drilling fluids or muds, those that are dissolved or entrained in the fluids which flow into a borehole when the pressure within the borehole is reduced, etc. The concentrations at which the hydrocarbons are present in relatively shallow earth formations tend to be very small, generally less than one part per million. Because of this, such previously proposed geochemical exploration procedures have tended to require costly operations, such as the careful collecting and preserving and analyzing of whole samples of the earth formations; or have tended to provide measurements that are difficult to correlate with respect to each other or with respect to other information, such as seismic information, relating to the region being explored.

SUMMARY OF THE INVENTION

In accordance with the present invention, earth formations are sampled by gas drilling boreholes into them while circulating a gaseous drilling fluid that is initially substantially free of a selected mobile reservoir fluid. The concentration of the mobile reservoir fluid in the earth formations around the borehole is measured by measuring the difference in its concentration in equivalent portions of the drilling fluid as the drilling fluid enters and leaves the borehole. Such measurements indicate the concentration of the mobile reservoir fluid with areal location and/or depth within the earth formations.

DESCRIPTION OF THE DRAWING

FIG. 1 is a schematic illustration of a system for practicing the invention.

FIG. 2 shows a multiple-port valve of the system of FIG. 1 with the ports in a different operational position.

DESCRIPTION OF THE INVENTION

FIG. 1 shows a gas drilling system comprising a rig structure 1, a drill string assembly 2, a gaseous-drilling fluid input line 3 (which is connected to a compressor or blower, not shown) a bit-cuttings separator 4, and a gas discharge sample line 5. A chromatograph 6 is arranged to measure the concentration of a selected mobile reservoir fluid in the inflowing gaseous drilling fluid before it has been circulated into borehole 7. A liquids and solids separator 8 is connected to receive and treat a portion of the gas being discharged from the bit-cuttings separator 4. The gas treated by separator 8 is supplied to a manifold 9. Manifold 9 preferably contains a filter means, such as a micropore dust filter, (not shown) for further cleaning the gas. A transfer pump 10 is connected to displace a sample stream of gas from the manifold 9 through a drying means 11 and into a multiport valve 12. The valve 12, in position shown, allows a sample stream of gas to flow through a sample trap loop 13 and exit through port 14.

As shown in FIG. 2, the position of the ports in valve 12 can be arranged so that the fluid in trap loop 13 is displaced

through chromatograph 15 and discharged through port 16. The displacement of the fluid from trap loop 13 is preferably effected by allowing an inflow of clean gas from a source 17 and outflow, ultimately through port 16, as indicated by the arrows. The pressure of the fluid displaced into chromatograph 15 is preferably regulated by a throttle valve 18 arranged upstream of discharge port 16 to maintain a pressure between that of a relatively high pressure at clean air source 17 and atmospheric pressure.

In a preferred arrangement, check valve 19 is placed upstream from multiport valve 12 to restrict backflow without significantly impeding forward flow. Pump 10 is preferably operated at substantially atmospheric pressure. If sample loop 13 is filled with clean gas at a higher pressure when it is connected to the outflow from check valve 19, the higher pressure is dissipated by a purge through discharge port 14 and the loop is refilled with undiluted sample gas at substantially atmospheric pressure.

Suitable chromatographs and chromatographic-measuring techniques are known. Examples of such devices and procedures are contained in U.S. Pat. Nos. 2,918,579; 3,116,133; 3,296,776 and 3,455,144.

In general, the gas drilling equipment used in the present invention can comprise substantially any such system which has been freed of the fluid being sampled to an extent such that only insignificant amounts are imparted to the gaseous drilling fluid that is circulated through the drilling system. In a preferred procedure the ensurance of this includes a hydrocarbon-removing treatment comprising contacting all portions of the drilling system that will be contacted by a circulating drilling fluid with a nonhydrocarbon solvent, such as an alcohol, ketone, ether, ester, or the like. All of the hydrocarbon lubricants are preferably replaced with non-hydrocarbon lubricants, such as the silicone oils and greases that are commercially available from Dow Chemical Company under the trademarks DC-200 (Oil) and DC-44 (Grease). In a preferred arrangement, the drilling fluid circulation is powered by a blower having fan blades mounted within a compartment that is isolated from the bearing. The drilling fluid circulating means is preferably arranged to intake relatively clean air from a substantially contaminant-free location, such as the top of the drilling rig. The drilling fluid exhaust or "blooey line" (not shown in the drawing) is preferably extended to a location that is both relatively remote from and downwind of the intake location.

In practicing this invention the measurement of the concentration of the selected fluid (such as a hydrocarbon) in the circulating drilling fluid, can be made by means of substantially any measuring device which is relatively sensitive and accurate with respect to concentrations of less than about one part per million. A chromatograph comprising a combination of a chromatographic column, a flame ionization detector, and an electrometer is a preferred type of such a measuring device. The sampling and analyzing of the drilling fluid before and after its circulation into the borehole can be performed by means of one or more such measuring devices. It is desirable that, at substantially each increment of depth of the borehole, at least one measurement before and after such circulation is made on the same portion (or on substantially equivalent portions) of the circulating gaseous drilling fluid. In the system shown in the drawing, for a given rate of drilling fluid circulation, a portion of an inflowing gas on which a measurement is made as the gas enters the drill string assembly 2 (by means of chromatograph 6) will, after a determinable length of time, become the gas that is filling the trap loop 13 of valve 12. The gas in the trap loop is isolated for measurement (by means of chromatograph 15) by changing the port arrangement of valve 12.

In field operations utilizing chromatographic measurements, it has been found that samples of about 10 cc. in volume are adequate, and such measurements can readily be repeated as often as every 15 seconds. At a typical drilling rate of about 6 feet per minute such a sampling rate provides a
